CLAIM

The ornamental design for a freestanding shoe rack, as shown and described.

DESCRIPTION

FIG. 1 is an orthographic projection of the freestanding shoe rack of the present invention;

FIG. 2 is an enlarged top plan view of the freestanding shoe rack;

FIG. 3 is a bottom plan view of FIG. 2;

FIG. 4 is a front elevation view of FIG. 2;

FIG. 5 is a rear elevation view of FIG. 2;

FIG. 6 is a right side elevation view of FIG. 2, the left side elevation view being a mirror image of the right side elevation view;

FIG. 7 is an orthographic projection of the freestanding shoe rack in alternate assembly, the sole difference being the rearwardly slanted placement of the shoe holding elements of the bottom rack; and,

FIG. 8 is an orthographic projection of the freestanding shoe rack in alternate assembly, the sole difference being the vertical placement of the shoe holding elements of the bottom rack.
